CLAIM

We claim the ornamental design for a bottle holder, as shown and described.

DESCRIPTION

FIG. 1 is a top perspective view of a bottle holder, showing our new design.

FIG. 2 is a top plan view of the bottle holder of FIG. 1.

FIG. 3 is a bottom view of the bottle holder of FIG. 1.

FIG. 4 is a front elevation view of the bottle holder of FIG.

1.

FIG. 5 is a rear elevation view of the bottle holder of FIG. 1.

FIG. 6 is a left side elevation view of the bottle holder of FIG. 1.

FIG. 7 is a right side elevation view of the bottle holder of FIG. 1; and,

FIG. 8 is a bottom perspective view of the bottle holder of FIG. 1.

The broken lines show portions of the bottle holder which form no part of the claimed design.

1 Claim, 6 Drawing Sheets
